HANDBAG

Oscar Wolf, Trenton, N. J.

Application April 27, 1953, Serial No. 24,674

Term of patent 7 years

(Cl. D87—3)

To all whom it may concern:

Be it known that I, Oscar Wolf, a citizen of the United States of America, residing in Trenton, county of Mercer, and State of New Jersey, have invented a new, original, and ornamental Design for a Handbag, of which the following is a specification, reference being had to the accompanying drawing, forming part thereof, wherein:

I claim:

The ornamental design for a handbag, substantially as shown and described.

OSCAR WOLF.
